United States Patent Office

Des. 228,164
Patented Aug. 21, 1973

228,164

CHAIR

Stapleton Long, Morristown, Tenn., assignor to The
Berkline Corporation, West Springfield, Mass.

Filed Mar. 20, 1972, Ser. No. 236,555

Term of patent 3½ years

Int. Cl. D6—02

U.S. Cl. D6—39

FIG. 1

FIG. 2

FIG. 3

FIG. 1 is a front elevational view of a chair embodying my new design;

FIG. 2 is a perspective view showing one of the two identical sides; and

FIG. 3 is a rear elevational view thereof.

I claim:

The ornamental design for a chair, as shown and described.
